To all whom it may concern:

Be it known that I, Tom P. Simovich, a citizen of the United States, residing at Arcadia, in the county of Los Angeles and State of California, have invented a new, original, and ornamental Design for a Lift Truck, of which the following is a specification, reference being had to the accompanying drawing forming a part thereof, in which:

Fig. 1 is a side view of a lift truck showing my new design;

Fig. 2 is a front perspective view; and,

Fig. 3 is a side perspective view thereof.

The dominant features of my design reside in the portions shown in full lines.

I claim:

The ornamental design for a lift truck, substantially as shown and described.
